UNITED STATES PATENT OFFICE.

HARRY J. KIGER AND WILLIAM A. HOHMAN, OF BELLINGHAM, WASHINGTON.

SAW-GUIDE.

No. 895,091.

Specification of Letters Patent.

Patented Aug. 4, 1908.

Application filed October 16, 1907. Serial No. 397,637.

To all whom it may concern:

Be it known that we, HARRY J. KIGER and WILLIAM A. HOHMAN, citizens of the United States of America, residing at Bell-
5 ington, in the county of Whatcom and State of Washington, have invented certain new and useful Improvements in Saw-Guides, of which the following is a specification.

This invention relates to new and useful 10 improvements in wood sawing and has relation more particularly to a saw holder to be employed with undercut saws.

In the event of a log lying up on two ele-
15 vated places at each end of the log it is im-
possible to saw the log from the top or that
portion which is sprung down as the log
would close upon the saw during the cutting
operation, but when the sprung portion is
20 cut from beneath the weight of the log will
open the cut made by the saw and thereby
assist in the operation.

It is an object of the invention to provide a
novel carriage to be employed in sawing a log
from the under side.

25 It is a further object of the invention to
provide in a device of this character novel
means whereby the cross cut saw will be held
in engagement with a log.

It is also an object of the invention to pro-
30 vide in combination with a device of this
kind, novel means whereby the carriage may
be held in operative position.

Furthermore, an object of the invention is
to produce a device of the character noted,
35 which will possess advantages in points of
simplicity, efficiency and durability, proving
at the same time comparatively inexpensive
to manufacture.

With the foregoing and other objects in
40 view, the invention consists in the details of
construction and in the arrangement and
combination of parts to be hereinafter more
fully set forth and claimed.

In describing the invention in detail, ref-
45 erence will be had to the accompanying
drawings forming part of this specification
wherein like characters denote correspond-
ing parts in the several views, in which—

Figure 1, is a view in side elevation illus-
50 trating the invention in applied position.
Fig. 2, is a view in front elevation of the
device with parts omitted. Fig. 3, is a view in
detail of a shaft employed in the invention.
Fig. 4, is a view in top plan of a detail of the
55 invention.

In the drawings, 1 denotes the base of a
steel frame approximately U-shaped in form.
Said frame has flat metal stems 2, bent adja-
cent the base in such manner as to cause the
edges of the same to aline.

Extending centrally through the base 1, of
the frame is an upright 3, terminating at its
upper end in a fork 4, in which is fixed a shaft
5. This shaft 5, projects beyond both sides
of the fork 4, and has its ends bifurcated as
65 at 6. This bifurcated portion of the shaft 5,
straddles the inner edges of the stems 2, and
thereby holds the upright 3, against any un-
due lateral movement with relation to the
base as will, it is thought, be fully under-
70 stood. The fork 4, forms with the upright 3,
a shoulder 7, against which bears a spiral
spring 8, which also contacts with the base 1,
of the frame. By means of this spring, an
upward pressure is constantly exerted against
75 the shoulder of the fork.

Loosely mounted on the shaft 5, is a
grooved wheel 9, and in one of the grooves
of the wheel is adapted to rest the back of a
cross cut saw 10. This wheel will readily
80 permit the reciprocation of the saw and as it
cuts its way in the log, the spring 8, will con-
stantly press the saw upwardly and hold the
teeth of the saw in contact with the log.

The upright 3, is provided in its lower end
85 with a cross pin 11, which is adapted to con-
tact with a washer 12, embracing the up-
right. This cross pin 11, limits the upward
movement of the upright.

Adjacent to the upper end of one of the
90 stems 2, is a perforation 13, through which
passes an end of a securing member 14, which
is suitably coiled as at 15, to hold the same
against displacement. The end of this mem-
ber 14, terminates in an inwardly inclined
95 pointed prong 16, which is forced into the log
to be operated upon and forms a spring an-
choring means for the upper portion of the
frame.

Secured to the under side of the base 1, is,
100 a cross piece 17, which projects beyond the
ends of the base and is coiled to form bear-
ings 18, for the approximately V-shaped fork
19; which terminates in points 20, which en-
gage the log to be operated upon and form a
securing medium for the lower portion of the
carriage. The fact that the fork 19, is ap-
proximately V-shaped prevents any undue
movement of the carriage during the course
105 of the operation. To prevent any outward
movement of the carriage during the course
110 of the operation.

movement of the carriage each member of the fork is provided with a sleeve 21, which is intended to abut a bearing 18. The sleeves 21, are connected by a cross bar 24, 5 and said cross bar is engaged by the hooks 25, of the arms 26, which are secured to the base of the frame by the securing bolts 23. The fork 19, is slideable loosely through the bearings 18, and the sleeves 21. This permits of a ready adjustment of the lower portion 10 of the carriage with relation to the log to be operated upon. When the desired adjustment has been attained the fork is held against movement by the set screws 22.

15 The cross piece 17, may be secured to the base 1, of the machine in any suitable or desired manner and as shown in the drawing bolts 23, are employed for the purpose.

What we claim is:

20 1. In a saw guide, a U-shaped frame, an upright movable through the base of the frame, a shaft carried by the upright projecting therebeyond and engaging the sides of the frame, a roller loosely mounted on the 25 shaft, means for moving the upright longitudinally and anchoring means for the frame.

2. In a saw guide, a U-shaped frame, an upright movable through the base of the 30 frame, a shaft carried by the upright projecting therebeyond and engaging the sides of the frame, a roller loosely mounted on the shaft, a spring contacting with the frame and the upright for imparting longitudinal 35 movement to the upright and anchoring means for the frame.

3. In a saw guide, a U-shaped frame, an upright movable through the base of the frame, a shaft carried by the upright, said 40 shaft having its ends bifurcated and embracing the sides of the frame, a roller loosely mounted on the shaft, means for imparting movement to the shaft longitudinally of the sides of the frame and anchoring means for 45 the frame.

4. In a saw guide, a frame, a supporting roller carried by the frame, an anchoring means carried by one end of the frame, bearings carried by the opposite end of the frame, 50 and an anchoring fork slideable within the bearings.

5. In a saw guide, a frame, a supporting roller carried by the frame, an anchoring

means carried by one end of the frame, bearings carried by the opposite end of the frame, 55 an anchoring fork slideable within the bearings, and means for holding the fork against movement through the bearings.

6. In a saw guide, a frame, a supporting roller carried by the frame, an anchoring 60 means carried by one end of the frame, bearings carried by the opposite end of the frame, an anchoring fork slideable within the bearings, sleeves embracing the fork, means for holding the sleeves against movement with 65 relation to the frame, and means carried by the sleeves for holding the fork against movement.

7. In a saw guide, a frame, a supporting roller carried by the frame, an anchoring 70 means carried by one end of the frame, bearings carried by the opposite end of the frame, an anchoring fork slideable within the bearings, sleeves embracing the fork, and means on the frame for holding the sleeves against 75 movement with relation to the frame and means carried by the sleeves for holding the fork against movement.

8. In a saw guide, a frame, a supporting roller carried by the frame, an anchoring 80 means carried by one end of the frame, bearings carried by the opposite end of the frame, an anchoring fork slideable within the bearings, sleeves embracing the fork, a bar connecting the sleeve, arms carried by the frame 85 engaging the bar and means carried by the sleeve for holding the fork against movement.

9. In a saw guide, a frame approximately 90 U-shaped an upright movable through the base of the frame, a fork on the upright, a spring embracing the upright bearing against the base of the frame and the base of the fork, a shaft carried by the fork operative therebeyond on both sides and engaging 95 the frame, a pulley loosely mounted on the shaft within the fork, and anchoring means carried by the frame.

In testimony whereof we hereby affix our signatures in the presence of two witnesses, 100 this 9 day of October 1907.

HARRY J. KIGER.

WILLIAM A. HOHMAN.
